DESIGN FOR A REFRESHMENT CART

Wolfgang Hoffmann, Batavia, Ill., assignor to The Howell Company, St. Charles, Ill., a corporation of Illinois

Application March 30, 1936, Serial No. 61,848

Term of patent 3½ years

To all whom it may concern:

Be it known that I, Wolfgang Hoffmann, a citizen of the Republic of Austria, residing at Batavia, in the county of Kane and State of Illinois, have invented a new, original, and ornamental Design for a Refreshment Cart, of which the following is a specification, reference being had to the accompanying drawing, forming a part thereof.

Figure 1 is a perspective view of the refreshment cart, showing my new design;
Fig. 2 is a top plan view thereof;
Fig. 3 is a side elevation thereof; and
Fig. 4 is a front elevation thereof.

I claim:

The ornamental design for a refreshment cart,
as shown.

WOLFGANG HOFFMANN.
